WITNESS:

Charles W. Brouse
INVENTOR
BY *Victor J. Evans*
ATTORNEY

UNITED STATES PATENT OFFICE.

CHARLES W. BROUSE, OF TYRONE, PENNSYLVANIA.

ATTACHMENT FOR SOCKET WRENCHES.

Application filed July 18, 1924. Serial No. 726,804.

To all whom it may concern:

Be it known that I, CHARLES W. BROUSE, a citizen of the United States, residing at Tyrone, in the county of Blair and State of Pennsylvania, have invented new and useful Improvements in an Attachment for Socket Wrenches, of which the following is a specification.

This invention relates to tools, particularly to socket wrenches, and has for its object the provision of a socket wrench and an attachment therefor whereby nuts backed off from bolts may be forcibly ejected from the socket instead of sticking therein as is so often the case.

An important object is the provision of a device of this character which will be simple and inexpensive in manufacture, positive in action, efficient and durable in service, and a general improvement in the art.

With the above and other objects and advantages in view, the invention consists in the details of construction to be hereinafter more fully described and claimed, and illustrated in the accompanying drawings, wherein:

Figure 1 is a side elevation of a socket wrench constructed in accordance with my invention,

Fig. 2 is a longitudinal section with a portion in elevation,

Fig. 3 is a front elevation, and

Fig. 4 is a detail cross-section on the line 4-4 of Fig. 2.

Referring more particularly to the drawings, I have shown my device as comprising an elongated shank 10 at one end of which is formed or secured a head 11 provided with a socket 12 of any desired configuration and size adapted to be engaged upon the nuts to be removed from bolts. Obviously, the socket may be engaged upon the heads of bolts if desired. At one side the shank is formed with an elongated groove 13 and the head is formed with a hole 14 registering with the groove for a purpose to be described.

Slidably mounted upon and encircling the shank 10 is a ring or collar 15 to which is

secured one end of an elongated rod 16 which is slidable through the hole 14 and which is formed at its other end within the socket 12 with a convolution 17 of any desired size and shape.

In the use of the device, it is apparent that when the socket 12 is engaged upon a nut or bolt head and the nut or bolt unscrewed in the usual manner, in order to effect ejection of the nut or bolt as the case may be, it is merely necessary that the operator press the collar or ring 15 toward the head 11, whereupon the coil or convolution 17 will engage against the nut or bolt head and force the same out of the socket. It is not really necessary that the ejector be actually retracted by hand inasmuch as engagement of the socket upon a nut or bolt head will act to force the ejector rearwardly.

From the foregoing description and a study of the drawings, it will be apparent that I have thus provided a very simple and inexpensive device for the purpose specified which will be highly efficient and which will be a great time and labor saver.

While I have shown and described the preferred embodiment of the invention, it should be understood that I reserve the right to make such changes in the form, construction, and arrangement of parts as will not depart from the spirit of the invention or the scope of the subjoined claim.

Having thus described the invention, I claim:

In a device of the character described, an elongated shank terminating at one end in a head having a socket therein adapted for engagement upon a nut or bolt head, the head having a hole therethrough extending into the socket and the shank having a groove alining with said hole, and an ejector including a rod slidably mounted along said groove and through said hole and terminating at one end in a convolution located within the socket, and a collar slidably surrounding the shank and secured to the other end of the rod.

In testimony whereof I affix my signature,
CHARLES W. BROUSE.
